The ornamental design for a diskette filing case, as shown and described.

DESCRIPTION

FIG. 1 is a perspective view of a diskette filing case showing my new design in a closed-door condition;

FIG. 2 is an enlarged front elevational view of the diskette filing case shown in FIG. 1;

FIG. 3 is an enlarged right elevational view of the diskette filing case shown in FIG. 1, the left side being a mirror image thereof;

FIG. 4 is an enlarged rear elevational view of the diskette filing case shown in FIG. 1;

FIG. 5 is an enlarged top plan view of the diskette filing case shown in FIG. 1;

FIG. 6 is an enlarged bottom plan view of the diskette filing case shown in FIG. 1;

FIG. 7 is an enlarged front elevational view of the diskette filing case shown in FIG. 1 with the index card removed for convenience of illustration; and,

FIG. 8 is a perspective view of the diskette filing case of FIG. 1 in an open-door condition and with a tray partially withdrawn.
